UNITED STATES PATENT OFFICE.

CHESTER C. COON, OF OAKLAND, CALIFORNIA.

CROSS-ARM CLAMP.

Application filed June 20, 1927. Serial No. 200,020.

My invention relates to such tools as are adapted to be used in connection with work required on high-voltage transmission lines, and it refers especially to a tool of this character, which is adapted to be clamped to a cross arm for assisting linemen in changing pin-type insulators or in installing new insulators of this type on the cross arm.

The main object of my invention is to provide a tool of this character, which is adapted to hold securely and in adjustable relation to the cross arm, while clamped thereto, a wire-engaging member, such as is known as a "pig-tail stick", so that a lineman is thereby enabled to support a wire and at the same time to change or install insulators on the cross arm with a minimum of hazard and without interrupting the service.

Another object of the invention is to provide a tool of this character, which may be easily and quickly secured in the required position on a cross arm and may be easily and quickly removed therefrom.

A further object of my invention is to provide a tool of this character, which is simple in construction and operation and may be manufactured cheaply so as to be sold at a low price.

Other objects and advantages will appear from the following detailed description of a preferred embodiment of the invention, which is illustrated in the accompanying drawings, it being understood that I reserve the right to make such changes and modifications in the form shown as come within the scope of the appended claims.

In the drawings:—

Figure 1 is a side elevation of a cross-arm clamp secured to a cross arm, shown sectionally, the clamp being shown as adjusted for securing between the jaws thereof a member, which holds therein a portion of a line wire;

Figure 2 is an end elevation of the cross-arm clamp, as viewed from the right of Figure 1, only a portion of the cross arm being shown, and the wire-engaging member being removed from the jaws in order to disclose otherwise hidden parts;

Figure 3 is a sectional plan taken in a plane indicated by the line 3—3 in Figure 1; and

Figure 4 is a broken end elevation of the cross-arm clamp, similar to Figure 2, but showing the frame swung to an angular position relative to the supporting member of the clamp.

In the preferred embodiment of my invention, the cross-arm clamp 1 comprises a supporting member 2, which is formed by side members 3 and 4, each preferably having a part thereof in the shape of a right-angled isosceles triangle, on which an outer extension 5 is formed integral with one cathetus 6, while another outer extension 7, substantially parallel with the extension 5, is formed at the junction of the other cathetus 8 with the hypotenuse 9, the extensions 7 being at their ends joined to a beam 10, provided with an edge 11, which is adapted to engage the upper side of a cross arm 12. In a similar manner the ends of the extensions 5 are joined by a beam 13, and approximately centrally therein, so as to register with the edge 11, is a threaded opening in which is screwed a stud 14, secured by any suitable means at one end of a handle 15, which preferably is of wood or some other suitable insulating material. At its free end the stud is pointed, as shown at 16, for the purpose of engaging the underside of the cross arm 12, so that, when the supporting member is in its clamping position upon the cross arm, a person, by turning the handle 15, may force the point of the stud into the cross arm and thus, while the edge 11 is sufficient for preventing a movement lengthwise of the cross arm, the stud 14 assures the clamping of the device 1, not only removably, but also in a non-slipping relation, to the cross arm.

Each of the side members 3 and 4 has at one end thereon an extension 17, joined to the cathetus 6 and aligned with the cathetus 8, and a strut 18 is preferably also made integral with the extension 17 and the cathetus 6 in order to strengthen the supporting member 2. At their ends, these extensions 17 are joined by a plate 19, and each of the side members 3 and 4 has at its end, opposite to the extension 17, another extension 20, joined to the cathetus 6 and at its initial portion preferably aligned with the hypotenuse 9, but having its terminal portion virtually parallel with the extension 17. A plate 2 is suitably joined to the extensions 20 and conforms thereto so that its terminal portion is virtually parallel with the plate 19, and a frame 22, which consists of spaced base members 23 and 24 having end members 25 and 26 respectively fixed thereto, fits with the end members on the respective plates 19 and 21 and is pivotally secured thereto by suitable and axially aligned pivotal means 27 and

28 so that the frame is thereby allowed to swing sidewise of the supporting member 2.

In order to secure a wire-engaging member 29, which in Figure 1 is illustrated as being 5 of the type known as a "pig-tail stick", to the frame 22, jaws 30 and 31 are provided, the inner faces of which are adapted to fit the handle 32 of the wire-engaging member, this 10 handle preferably being of wood or some other suitable, insulating material, so as to enable a lineman to hold a line wire 33 in the hook portion 34 of the wire-engaging member with safety and without shutting off the electric current. The outer jaw 31 is 15 preferably formed with a curved outer face adapted to be engaged by the curved portion 35 of a yoke 36 having virtually parallel bars 37, which extend from the curved portion through respective registering openings in 20 the jaws and in the end member 26 and also through respective registering openings in a plate 38, arranged transversely to the frame, and the bars have screwed thereon at their ends nuts 38', so that the yoke is in a reciprocative 25 relation to the frame 22 and that the plate and the outer jaw 31 are adapted to follow the respective movements of the yoke, while the inner jaw 30 is adapted to reciprocate upon the bars 37 thereof, the positioning 30 of the yoke being preferably in a plane, transverse, and substantially at right angles, to the frame, as shown in Fig. 1.

A clevis 39, comprising side members 40 bent at right angles to an end member 41, is 35 connected with the plate 38, the members 40 being virtually parallel with the bars 37 of the yoke 36 and with the base members 23 and 24 of the frame 22. In this instance, the connecting means for the clevis is shown as a stud 40, provided with a shouldered portion 42, 40 slidably extending through an opening in the end member 25 of the frame, and with a reduced portion extending through an opening in the member 41 of the clevis, the reduced end of the 45 stud 42 being threaded and having a nut 43 screwed thereon, so that the member 41 of the clevis is pressed against the plate 38, and the latter is pressed against the shouldered portion of the stud 42, and the clevis and the plate 50 are thereby fixed to each other and movable together. At the outer end of its shouldered portion, the stud 42 is provided with a head 44, adapted to abut against the outer face of the end member 25 in order to limit the inward 55 movement of the plate 38 and the clevis 39 from the end member.

For the purpose of causing a reciprocal motion of the outer jaw 31, a rod 45 fits at one end with a bearing member 46 between the 60 side members 40 of the clevis 39 and is pivotally secured thereto by a pin 47. At its other end the rod 45 has a similar bearing member 48, which fits between the corresponding ends of duplicate side members 49 of a lever 50 and is pivotally secured thereto by a

pin 51. The other corresponding ends of the side members 49 of the lever are pivotally secured by any suitable means, such as a pin 52, 70 to and between ears 53, formed correspondingly on the base members 23 and 24 at their junction with the end member 26 of the frame 22, and a block 54 may be provided on the pin 52 for holding the side members 49 in a correct spaced relation to each other and for maintaining a sufficient side play for the lever 50 so as to allow the lever to swing freely 75 within the frame.

Between the side members 49 of the lever 50 and at a suitable intermediate portion thereof 80 is a block 55, which is internally threaded and at its side provided with trunnions 56, rotatably extending through registering openings in the side members 49, so that the block is turnable within the lever 50. A stud 57 is at one end provided with a screw-threaded portion 58, engaging the block 55, and with an intermediate, shouldered portion 59 and has at its other end an unthreaded cylindrical portion 60 fitted in a ferruled portion 61 at one end of a handle 62, which is preferably made 90 of wood or some other suitable insulating material, and the stud is secured to the ferrule by any suitable means, such as a cotter pin 63, in order that the stud and the handle may be easily attached to, or removed from, each other. Upon the unthreaded portion 60 is slidably fitted a block 64, which is at its side provided with trunnions 65, rotatably extending through registering openings in the 100 respective base members 23 and 24 of the frame 22, and, preferably, a collar 66 is also slipped upon the unthreaded portion 60 between the block 55 and the end of the ferrule 61, so that, while a free turning movement is allowed the handle 62, an unnecessary end play of the stud is prevented and thus makes the lever 50 immediately responsive to every turning movement of the handle.

The plate 21 has preferably therein a cut-out portion 67 in order to allow a considerable 110 swinging movement of the frame 22 before the bars 37 of the yoke 36 contact the side edges of the plate and thereby limit the swinging of the frame sidewise of the supporting member 2. In the plate are also formed holes 68, which are spaced from one another and are arranged in a circle concentric with the pivot 28, and the inner jaw 30 has thereon a pair of dowel pins 69 in parallel relation to the bars 37 and slidably extending through 120 holes, which are formed in the end member 26 of the frame 22 and are adapted to register with the respective holes 68, so that the dowel pins may slidably engage the holes 68 in selected positions and thus lock the frame 22 in various angular positions relative to the supporting member 2. Another pair of dowel pins 70 is preferably also provided on the inner jaw 30 so as to extend slidably through respective openings in the end 125 member 26.

member 26 of the frame 22, and preferably arranged around the bars 37 and between the end member 26 and the jaw are respective coil springs 71, by which the jaw is normally urged away from the end member, and the dowel pins 69 are caused to be normally out of engagement with the holes 68 in the plate 21. The jaw 30 has threaded thereinto a bolt 72, which with its shank extends slidably through an opening in the end member 26. Upon this bolt is screwed a nut 73, which serves to limit the movement of the jaw toward the end member, while the head 74 of the bolt limits the movement of the jaw away from the end member so that the dowel pins 69 and 70 can not become disengaged from the end member when the jaw is moved outward from the frame 22.

Preferably on the hypotenuse 9 of the side member 3 of the supporting member 2 and at the junction of the hypotenuse with the extension 7, the supporting member is provided with a hook 75. A lineman is thereby enabled to suspend the cross-arm clamp 1 on a line wire 33 or other support, when he is working with other tools, and to conveniently reach the cross-arm clamp, when he again is in need thereof.

If the end portion 58 of the stud 57 is provided with a right-hand thread, as shown in Figure 1, a turning of the handle 62 in the direction indicated by the curved arrow in Figure 3 will result in moving the block 55 toward the shouldered portion 59. Thus, if the handle 32 of the wire-engaging member 29 is inserted between the jaws 30 and 31, such a turning movement by the connection of the outer jaw 31 with the yoke 36 and by the connection of the latter with the lever 50 and the plate 38, will result in forcing the jaw 31 toward the inner jaw 30 against the pressure of the springs 71. It being assumed that the cross-arm clamp 1 is secured to the cross arm 12 by the pointed stud 14 on the handle 15 and the edge 11 on the beam 10, as before described, the lineman—before the engagement of the dowel pins 69 with the respective holes 68 in the plate 21 occurs—by taking hold of the handle 32 of the wire-engaging member, can adjust the latter to the most suitable angular position for holding the line wire 33 in the hook portion 34 thereof.

When the dowel pins 69 are in registering positions with the respective holes 68 for effecting the desired angular position of the frame 22 relative to the supporting member 2, as suggested in Figure 4, he simply continues to turn the handle 62 until the nut 73 abuts against the plate 21 and the jaws are thereby prevented from a farther inward movement toward the end member 26 of the frame 22, thus securely holding the wire-engaging member 29 in its required position to the frame simultaneously with the locking of the frame in the required angular position to

the supporting member without necessitating the shutting off of the electric current, and thereby enabling the lineman to proceed with the changing or the installing of insulators on the cross arm or with whatever other work in connection with high-voltage transmission lines he may be required to perform thereon.

In order to remove the wire-engaging member from the jaws, the handle 62 is turned in the opposite direction to that indicated by the curved arrow in Figure 3, the head 74 of the bolt 72 then limiting the outward movement of the inner jaw 30, and the head 44 on the stud 42, by its abutment against the end member 25, limiting the outward movement of the yoke 36 and thus preventing the dowel pins 69 and 70 from sliding out of engagement with the end member 26.

I claim as my invention:

1. A cross-arm clamp of the character described, comprising a supporting member; means for removably clamping the member to the cross arm; means pivotally secured to the supporting member so as to be swingable to various angular positions for removably securing a wire-engaging member to the supporting member; means for holding the wire-engaging member in various angular positions relative to the supporting member; and means for locking the wire-engaging member in any of the angular positions.

2. A cross-arm clamp of the character described, comprising a supporting member; means for removably clamping the member to the cross arm; a frame pivotally secured to the supporting member so as to be adapted to be swung to various angular positions relative to the supporting member; means for removably securing a wire-engaging member to the frame; and means for locking the frame in any of the angular positions.

3. A cross-arm clamp of the character described, comprising a supporting member; means for removably clamping the member to the cross arm; a frame pivotally secured to the supporting member so as to be adapted to be swung to various angular positions relative to the supporting member; means for removably securing a wire-engaging member to the frame; and means for locking the frame in any of the angular positions simultaneously with the securing of the wire-engaging member to the frame.

4. In a cross-arm clamp of the character described, a frame adapted to be removably clamped to the cross arm; a pair of jaws secured to the frame so as to allow one jaw to reciprocate in order to adapt the jaws to hold a wire-engaging member therebetween; and means for reciprocating the reciprocal jaw so as to allow the wire-engaging member to be slid to any desired position between the jaws and to be firmly secured by them to the frame, or to allow the wire-engaging member to be released from its engagement with the jaws.

5. In a cross-arm clamp of the character described, a frame adapted to be removably clamped to the cross arm; a pair of jaws secured to the frame so as to allow one jaw to 5 reciprocate in order to adapt the jaws to hold a wire-engaging member therebetween; a lever pivotally connected with the frame and pivotally connected with the reciprocal jaw; and a handle having a pivotal and screw-threaded connection with the lever and a pivotal and screw-threaded connection with the frame, so that, by the turning of the handle, the reciprocal jaw may be moved so as to allow the wire-engaging member to be slid to any 10 desired position between the jaws and to be firmly secured by them to the frame, or to allow the wire-engaging member to be released from its engagement with the jaws.

6. In a cross-arm clamp of the character described, a frame adapted to be movably clamped to the cross arm; a pair of jaws secured to the frame so as to allow one jaw to reciprocate in order to adapt the jaws to hold a wire-engaging member therebetween; 20 means for reciprocating the reciprocal jaw so as to allow the wire-engaging member to be slid to any desired position between the jaws and to be firmly secured by them to the frame, or to allow the wire-engaging member 25 to be released from its engagement with the jaws; and means for limiting the movement of the reciprocal jaw away from the other jaw.

7. A cross-arm clamp of the character described, comprising a supported member provided with an extension at each end; means for removably clamping the member to the cross arm; a frame pivotally secured to the extensions so as to be adapted to be swung 30 to various angular positions relative to the supporting member; means for removably securing a wire-engaging member to the frame; and means connected with the securing means and adapted to engage one of the 35 extensions so as to lock the frame in any of the angular positions when the securing means is in a position for holding the wire-engaging member.

8. A cross-arm clamp of the character described, comprising a supporting member provided with an extension at each end; means for removably clamping the member to the cross arm; a frame pivotally secured to the extensions so as to be adapted to be swung 40 to various angular positions relative to the supporting member; means for removably securing a wire-engaging member to the frame; means connected with the securing means and adapted to engage one of the extensions so as 45 to lock the frame in any of the angular positions when the securing means is in a position for holding the wire-engaging member; and means for operating the securing means.

9. A cross-arm clamp of the character described, comprising a supporting member

provided with an extension at each end; means for removably clamping the member to the cross arm; a frame having end members pivotally secured to the respective extensions so as to adapt the frame to be swung to various angular positions relative to the supporting member; an inner and an outer jaw mounted so as to be adapted to slide to or from one of the end members and outside thereof; means connected with the outer jaw for sliding the outer jaw to or from the inner jaw so as to adapt the jaws to hold a wire-engaging member removably therebetween; dowel means connected with the inner jaw and extending through the last mentioned end member and being adapted to extend through spaced openings in the extension on the supporting member adjacent to the last mentioned end member for locking the frame in various angular positions relative to the supporting member when the inner jaw is slid toward the last mentioned end member; spring means mounted so as to urge the inner jaw away from the last mentioned end member and thus to urge the dowel means normally out of locking engagement with the respective extension on the supporting member; and means for operating the outer jaw.

10. A cross-arm clamp of the character described, comprising a supporting member provided with an extension at each end; means for removably clamping the member to the cross arm; a frame having end members pivotally secured to the respective extensions so as to adapt the frame to be swung to various angular positions relative to the supporting member; an inner and an outer jaw mounted so as to be adapted to slide to or from one of the end members and outside thereof; means connected with the outer jaw for sliding the outer jaw to or from the inner jaw so as to adapt the jaws to hold a wire-engaging member removably therebetween; dowel means connected with the inner jaw and extending through the last mentioned end member and being adapted to extend through spaced openings in the extension on the supporting member adjacent to the last mentioned end member for locking the frame in various angular positions relative to the supporting member when the inner jaw is slid toward the last mentioned end member; other dowel means connected with the inner jaw and slidably extending through the last mentioned end member so as to adapt the jaws to be swung with the frame and to hold the wire-engaging member between them in various angular positions in correspondence with the angular positions of the frame; spring means mounted so as to urge the inner jaw away from the last mentioned end member and thus to urge the first mentioned dowel means normally out of locking engagement with the respective extension on the supporting member; and means for operating the outer jaw.

11. A cross-arm clamp of the character described, comprising a supporting member provided with an extension at each end; means for removably clamping the member 5 to the cross arm; a frame having end members pivotally secured to the respective extensions so as to adopt the frame to be swung to various angular positions relative to the supporting member; an inner and an outer jaw mounted 10 so as to be adapted to slide to or from one of the end members and outside thereof; means connected with the outer jaw for sliding the outer jaw to or from the inner jaw so as to adapt the jaws to hold a wire-engaging member 15 removably therebetween; dowel means connected with the inner jaw and extending through the last mentioned end member and being adapted to extend through spaced openings in the extension on the supporting member adjacent to the last mentioned end member for locking the frame in various angular positions relatively to the supporting member 20 when the inner jaw is slid toward the last mentioned end member; spring means mounted so as to urge the inner jaw away from the last mentioned end member and thus to urge the dowel means normally out of locking engagement with the respective extension on the supporting member; means for operating the outer jaw; and means for limiting the 25 sliding movements of the jaws.

In testimony whereof I affix my signature.

CHESTER C. COON.
